UNITED STATES PATENT OFFICE.

RICHARD W. UHLIG, OF RUTHERFORD, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

974,314.

Specification of Letters Patent. Patented Nov. 1, 1910.

Application filed December 27, 1909. Serial No. 534,948.

To all whom it may concern:

Be it known that I, RICHARD W. UHLIG, a citizen of the United States, residing in Rutherford, in the county of Bergen and State of New Jersey, have invented certain new and useful Improvements in Type-Writing Machines, of which the following is a specification.

This invention relates to tabulating mechanisms for typewriting and other machines.

One object of the invention is to provide simplified and improved means for selecting the stop, (preferably the column stop) by which the carriage is to be arrested at the tabulating operation. To this end, the stops are constructed to engage successively the teeth of a pinion to rotate the same intermittently; and a disk is connected to said pinion and provided with a volute series of stops; key-operated selecting devices being provided to determine by which of the volute stops, and hence by which of the column stops, the carriage is to be arrested; thus enabling the operator to move the carriage at once to position for writing in the desired column, skipping the intervening columns. The device which arrests said set of volute stops is preferably in the form of a single stop, which is variably movable by the tabulating keys, so that it may be projected into the path of any desired volute stop by simply depressing the corresponding key.

Another object of the invention is to simplify the construction of the machine, particularly with a view to reducing the number of keys. Usually the tabulator keys form a set separate from the type-operating keys; and it is usually found inconvenient to arrange this extra set of keys upon the machine. I have contrived to dispense with the extra set of keys, and to employ the figure keys for tabulating, that is to say, the keys on the keyboard, which are usually employed to throw the figure types against the platen. In carrying out this feature of the invention, I provide tabulating devices which are normally inoperable by the figure keys, so that the latter may perform their function in the usual manner, of throwing the figure types against the platen, without regard to the tabulating mechanism. When, however, it is desired to operate the tabulating mechanism, a special key is depressed which shifts the tabulating devices to po-

sition to be actuated by said figure keys; so that for instance when the key 4 is depressed, the carriage is immediately shifted to position for writing in the fourth column on the page.

Preferably the tabulator stop devices are controlled by a set of arms, which are shiftable into and out of position to be operated by the type-operating figure keys. They are preferably shifted as a set by means of a single key-bar, which extends along behind the usual row of figure keys at the back of the keyboard but close to said keys, so that both the key-bar and any figure key may be depressed by a single stroke of the finger. Hence when the operator wishes to write instead of tabulating, he simply depresses a figure key in the usual manner; but when he wishes to tabulate instead of writing, he depresses said key-bar simultaneously with the selected key; means being provided to prevent the key from throwing the type against the platen at the tabulating operation. Said set of tabulating arms is preferably a rigid structure and acts variably upon a single stop to project the latter to different positions for engaging the different volute stops as already described; and for releasing the carriage at the tabulating operation there is employed a universal bar directly engageable by the figure key levers and movable the same distance by all of said levers; provision being made for preventing the universal bar from releasing the carriage except at the tabulating operation.

Other features and advantages will hereinafter appear.

In the accompanying drawings, Figure 1 is a perspective front view, partly broken away, of sufficient of an Underwood front strike writing machine, to illustrate the principal features of the present improvements. Fig. 2 is a bottom view of the machine. Fig. 3 is a sectional longitudinal elevation taken about centrally thereof. Fig. 4 is a front elevation of the carriage stop devices and certain of the releasing devices. Fig. 5 is a front sectional view showing more clearly the check for the stop pinion which is here illustrated in its normal position. Fig. 6 is a view similar to Fig. 4, but illustrating the carriage as arrested by the tabulating devices. Fig. 7 shows a set of the shiftable arms, whereby the figure keys may operate the tabulating stop de-

5 vices; these arms being shown out of line to illustrate their gradually increasing lengths or heights. Fig. 8 is an enlarged diagram to illustrate the manner in which the column stop rotates the stop pinion. Fig. 9 is a view to illustrate the cam action, whereby the key bar is enabled to shift the stop-operating arms into and out of the paths of the figure key levers.

10 At the keyboard of the typewriter, a row of keys 11, usually placed in the rear bank, is shown, said keys mounted on levers 12 pivoted at 13 and having wrists or projections 14 to engage slots formed in bell cranks 15, the latter engaging type bars 16 to throw the figure types 17 against a platen 18; the usual springs 19 serving to turn the parts to normal positions.

15 The type bars operate the usual universal bar 20 to effect the feeding of a carriage 21 upon which the platen 18 is mounted; the carriage having a rack 22 mounted on said carriage by means of arms 23, and engaging a pinion 24, to which is connected the usual 25 escapement wheel (not shown), whose movements are controlled by dogs (not shown) connected to said universal bar 20, whereby the carriage is fed step by step every time that a type bar is swung to and from 30 the platen.

Upon the carriage is mounted a rack bar 25, into which are set, at any desired intervals, similar column stops 26, which may be for instance ten, in number, to permit the 35 writing of ten columns on the page. These column stops project below the bar in position to engage the teeth of a pinion 27, to rotate the same intermittently as the carriage advances in letter-feeding direction or 40 to the left at Figs. 4 and 6. To said wheel is fixed a plate 28, carrying ten stops or facets 29 having volute arrangement, the first stop being nearest the axis of revolution, the next stop farther from said axis, 45 the next still farther, and so on, the last stop in the series being the most remote from said axis. Said pinion and its stop disk turn upon a shaft 30 journaled in the framework of the machine. There is provided a key-operated stop 31, normally below all of the volute stops 29, as at Fig. 4, so as not to interfere with the rotation of 50 said pinion by said column stops 26, during the ordinary letter-feeding and return movements of the carriage 21; but by means presently to be described said stop 31 may be elevated to any desired extent, so as to bring it into the path of any one of the 55 volute stops 29, thereby to arrest the stop disk 28, the pinion 27 and the column stop 26, which is at the moment in engagement with the pinion, said column stop being the one which corresponds to the volute stop 29 that is arrested by the stop 31. When the 60 stop 31 is thrust up to its highest position, 65

it will be in position to engage the first volute stop 29 in the series, and hence to arrest the disk 28, the pinion 27 and the carriage 21, upon the engagement of the first column stop 26 with said pinion. Or if 70 said stop is thrust up only enough to get into the path of the last volute stop 29, then all the column stops 26 except the last one in the series will turn said pinion 28 idly, and when the last column stop engages said 75 pinion the last volute stop 29 engages the stop 31, thereby arresting the carriage in position to begin writing in the last column on the page. It will also be understood that by thrusting said stop 31 up to any desired 80 intervening point, the carriage will be arrested by the co-action of the corresponding column stop with the pinion 28. Thus the operator may determine at which column 85 he desires the carriage to be arrested.

There is shown herein one means of effecting variable movements of the stop 31 for the purposes just described; but it will be understood that said stop may be set by other means, and also that the herein described key-operated devices may be used in connection with other stops than stop 31, or with other systems of stops, for either column-skipping or decimal-tabulating, as may be desired. Said stop 31 is in the form of a plate mounted for vertical sliding movement and rigidly connected by a member 32 to a lower rod 33; and the latter is engaged by the rear end of an arm 34 extending from a rock shaft 35, journaled at its ends in the opposite base portions 36 of the framework of the machine. Means will now be described whereby said figure keys are enabled to rock said shaft 35 variably for the purpose of elevating the stop 31 to different positions, whereby the carriage may be variably arrested as already set forth. Fixed upon said rock shaft and extending forwardly therefrom are arms 37 at intervals agreeing with the intervals between the figure key levers 12, but normally lying to one side of said levers as at Fig. 2, so as not to be operable thereby. Hence during the ordinary operation of the figure types, the tabulating mechanism is not affected. Said rock shaft 35 is movable endwise in its bearings to bring all of the arms 37 simultaneously beneath their associated figure key levers 12, so that upon depression of any figure key its lever 12 will bear down that arm 37 which is directly beneath the same, and hence rock the shaft 35 and lift the stop-operating arm 34 fixed thereon. In order to secure the desired variable throw of the arm 34 and stop 31 the arms 37 may be of various lengths or heights as seen best at Fig. 7, the longest arm being associated with the first lever 12, whose key bears the numeral "1." Depression of this key will therefore give the rock shaft 35 the greatest movement, and hence the stop 90 95 100 105 110 115 120 125 130

31 will be thrown up into position to engage the first volute stop 29, so as to arrest the carriage when the first column stop 26 is in engagement with the pinion 27. The arms 5 are progressively shorter beginning with said first arm; and if there are ten of said arms the shortest one will be beneath the key marked "0" at the right hand end of the row of figure keys, and depression of 10 said key would cause the carriage to be arrested in position to begin writing in the tenth column on the page, since the rock shaft would be given the greatest extent of movement, and the stop 31 would be lifted 15 only far enough to engage the last volute stop 29 of the set, and hence all of the first column stops would pass idly by the pinion 27.

The shifting of the stop-operating arms 20 37 to effective positions is effected by a key-bar 38, extending along the row of figure keys 11, and pivoted by a pair of stems 39 upon a pair of arms 40 extending forwardly from a rock shaft 41 parallel with the rock 25 shaft 35. An arm 42 is fixed on the rock shaft 41 and carries at its rear end a finger 43 normally lying below a cam block or collar 44 fixed upon the main rock shaft 35. Said cam block 44 normally overlies said finger 43; but upon depression of the key 38, the shaft 41 is rocked and the arm 42 lifted. Said finger 43 engages a cam or inclined surface 45 upon said block 44, and cams the shaft 35 to the right together with the arms 30 37 fixed thereon. This movement occurs during the initial portion of the depression of the key-bar 38. During the final portion of said depression the finger 43 engages a vertical face or dwell portion 46 provided 35 upon said cam block 44, to lock or detain said rock shaft 35 in its shifted position, as at Fig. 1. A stop 47 may be provided for the arm 42. The key-bar 38 is placed very close to the keys 11, so that both the key-bar and any selected key may be depressed by a single downward stroke of the finger, which may engage both the key-bar and the key at the same time, owing to their proximity. The first portion of the stroke of the 40 key-bar occurs before the finger strikes the key 11, and hence the stop-operating arms 37 are cammed or shifted to positions beneath the key levers 12 before the latter are depressed. During the remainder of the depression of the key-bar and key, the finger 43 merely serves to hold the arms 37 in their shifted positions. A spring 48 returns the key-bar, and a spring 49 coiled about the end of the shaft 35 serves both to shift the latter endwise back to normal position, and also to rock the rock shaft back to its initial 45 rotative position.

For releasing the carriage, which as usual is power-driven, from the control of its escapement devices, there is provided a universal

bar 50 extending beneath all of the key levers 12 and always operable thereby, although such operation is idle, unless the stop devices have been shifted to effective positions. This universal bar 50 is provided 70 at its ends with arms 51, whereby it is loosely hung upon the rock shaft 35. From one of said arms projects backwardly an extension or arm 52, the rear end of which engages and lifts a vertical bar 53 intended to release the carriage 21; being for this purpose provided with a lug 54 to lift an arm 55 provided upon the usual rock shaft 56, the latter connected by arm 57 and vertical link 58 with a lever 59, carrying the usual roll 60 80 for lifting the rack 22 out of mesh with the pinion 24, to permit the advance run of the carriage independently of the letter-spacing devices. The rock shaft 56 is also usually provided with a brake barrel 61 operating in 85 the usual manner.

The arm 52 is intended to move with the rock-shaft 35 when the latter is shifted endwise; and for this purpose the universal bar arm 51 is provided with a tongue 62, which 90 engages a peripheral groove 63 (Fig. 2), permitting independent rocking of the arm 51, but causing the latter to shift with the rock shaft when the latter moves endwise. Normally the carriage-releasing arm 52 lies 95 to one side of the vertical releasing bar 53, as at Fig. 2, so that the idle vibrations of the universal bar 50, during the operation of the figure types, have no effect upon the carriage-releasing mechanism. When said rock 100 shaft is shifted to the right, however, the arm 52 is brought into position to engage the releasing bar 53 upon the depression of the universal bar 50, so that the carriage is released preparatory to being arrested by 105 means of the stop mechanism already described.

Extending back from the universal bar arm 51 is an arm 64, which, when the universal bar is shifted to the right, engages a 110 stop 65 to limit the throw of all of the key levers 12, one purpose being to provide for accurate positioning of the stop 31, and another purpose being to arrest the levers 12 before the types 17 reach the platen, so that 115 no impressions will be made by the types upon the paper at the tabulating operation of the carriage. When the tabulating mechanism is in normal ineffective position, the arm 64 plays idly up through a notch 120 66 in the stop or ledge 65. A spring 67 is provided for returning the universal bar 50 to normal elevated position.

Referring again to the pinion 27, it will be seen that the same is locked against backward movement by a pawl 68 pivoted to the framework at 69 and having a spring 70, whereby it is normally pressed into engagement with the pinion teeth. Formed upon said pawl is an arm 71 having a double cam 125

or projection 72 in the path of the column stops 26, to enable the latter, whether traveling backwardly or forwardly, to depress the arm 71 and the pawl 68, to disengage the latter from the pinion. The latter may also be provided with a spring check 73 to seat between adjacent teeth for positioning the pinion. A stop 74 may be provided to limit the return movement of the pinion 27 and 10 volute stop disk 28. Springs 75 and 76 may be provided for returning the members 33 and 53 respectively.

When the key 11 is depressed alone, its lever 12 descends and rocks the bell crank 15 15, thereby swinging the type against the platen. When the operator desires to use the key 11 for tabulating instead of printing, he strikes the key-bar 38 at a point just back of the key 11 which corresponds with 20 the column to which it is desired to set the carriage 21. At the first part of the depression of the key-bar 38, the shaft 41 is rocked and the finger 43 on the arm 42 engages the cam 45 and thrusts the rock shaft 25 35 to the right together with the arms 37 thereon, so that the latter occupy positions directly beneath the respective key levers 12. The operator's finger now strikes the selected key 11 and carries it down, together 30 with the key-bar 38; the remainder of the depression of said key-bar being idle, and the finger 43 merely engaging the dwell 46 on the cam block 44 to maintain the rock shaft 35 in its shifted position.

35 During the stroke of the key, the descending lever 12 engages the arm 37 directly beneath the same, thereby swinging said arm together with said rock shaft 35. By this means the rearwardly extending arm 34 is 40 raised, and the stop members 33, 31 are lifted accordingly so that the stop 31 is brought to position to arrest the first, second, third or other volute stop 29, to correspond with the key 11 that is depressed.

45 During the described shifting movement of the rock shaft 35, the arm 64 is shifted into position beneath the stop 65, so as to limit the swinging movement of the universal bar 50, and hence to arrest the type 50 17 a short distance from the platen, as well as limit the upward movement of the stop 31. The arm 52 is also shifted at the same time into position beneath the carriage-releasing bar 53; so that during the descent of 55 the lever 12 said bar is raised and the carriage is released by means of the train of mechanism 55 to 60. The carriage being released, runs forward, the pinion 27 being advanced intermittently by the column stops 60 26; each column stop engaging the cam 32 on the pawl 68 to depress the same and clear the pinion therefrom. The pinion and the set of volute stops 29 turn until the selected stop 29 engages the stop 31, whereupon the 65 carriage is arrested, as at Fig. 6. Upon re-

lieving the key 11 and the key bar 38 from pressure, the key-operated parts return to normal positions. The operation may be repeated until the line of writing is completed. Upon returning the carriage to position to 70 begin a new line, the column stops 26 successively engage the cam 72 to release the pinion 27, and permit it to be rotated backwardly together with the volute stops 29 by means of the column stops 26. An ear 76^a 75 may be bent over from the bar 53 to rest upon a shoulder 76^b formed on the member 33, to serve as a stop to arrest the member 53 in its descent; although the member 33 does not serve to raise the member 53, the latter rising ahead of the former at the tabulating operation.

Whenever it is desired to proceed regularly from each column to the next without skipping intervening columns, a single key 85 may be employed, so as to relieve the operator from the trouble of remembering the numbers of the respective columns. For such use the key 11 which is marked "1" 90 may be used. Preparatory to said use the latch 32 should be swung backwardly to the position seen at Fig. 1, so as to release the projection 77 upon the stop 31, and normally engaged by said latch; the latter pivoted at 78 to the member 33. A spring 79 95 coiled about a vertical pin 80, and confined between an ear 81 on the member 33, and an ear 82 on the stop 31, serves to hold the stop up; the movement of the stop by the spring being limited by an ear 83 provided on the stop 31 and engaging a head 84 provided on the vertical pin 80.

Owing to the volute shape of the stop-carrying disk 28, the stop 31 will usually be 105 prematurely arrested if the key "1" is employed for spacing from column to column in the manner just suggested; but in such cases the spring 79 may yield to permit the member 33 to complete the ascent after the stop 31 is arrested by engagement with the periphery of said stop-carrying disk 28.

The latch 32 may, if desired, be omitted altogether, and it will be found that all the keys marked 1 to 0 will operate in the manner described in the preceding portion of 115 this description, since the spring 79 will always hold the two-part member 33 fully extended. On the other hand the spring 79 may if desired be omitted, and the parts 31 and 33 be made in a single piece within the 120 scope of the invention.

Variations may be resorted to within the scope of the invention, and portions of the improvements may be used without others.

Having thus described my invention, I 125 claim:

1. In a tabulating mechanism, the combination with a series of column stops, of a pinion rotatable by the column stops, a set of stops having a volute arrangement and con- 130.

nected to said pinion, a set of keys, and a variably movable stop mechanism controlled by the set of keys to be projected thereby variable distances into the path of said volute stops for variably arresting the same.

2. In a tabulating mechanism, the combination with a series of column stops, of a pinion rotatable by the column stops, a set of stops having a volute arrangement and connected to said pinion, a single stop, a series of keys, and means for enabling said keys to project said single stop variable distances into the path of said volute stops for variably arresting the same.

15 3. In a tabulating mechanism, the combination with a series of column stops, of a pinion rotatable by the column stops, a single pawl to prevent rotation of the pinion, and a spring for said pawl; the latter having opposite cams engageable by the column stops during the movements of the carriage in opposite directions, for releasing the pinion from the control of said pawl.

4. In a typewriting machine, the combination with a set of type-operating figure keys, of a carriage, a tabulating mechanism for said carriage, a bar extending along the set of keys in position to be depressible by the same stroke of the finger that depresses any key, and means for enabling said bar to connect said tabulating mechanism to the depressed figure key to be operated thereby.

35 5. In a typewriting machine, the combination with a set of type-operating figure keys, of a carriage, a tabulating mechanism for said carriage, a bar extending along the set of keys in position to be depressible by the same stroke of the finger that depresses any key, and means for enabling said bar to connect said tabulating mechanism to the depressed figure key to be operated thereby; means being connected to said bar to prevent the figure types from printing at the tabulating operation.

45 6. In a typewriting machine, the combination with a set of figure keys, corresponding types connected thereto, a carriage and a tabulating mechanism, of means controllable by the same stroke of the finger that operates any key, for enabling said keys to operate the tabulating mechanism without causing the types to print.

55 7. In a typewriting machine, the combination with a set of figure keys and types connected thereto, of a carriage, a tabulating mechanism for said carriage, and a bar at the keyboard extending along said keys and connected to means operable at the initial portion of the depression of the bar for operatively connecting said tabulating mechanism to any figure key to be operated thereby during the remainder of the depression of the bar.

65 8. In a typewriting machine, the combination with a set of keys, a set of levers oper-

ated thereby, and a carriage, of a set of arms normally inoperable by said levers, a bar extending along said keys to be operated by the same finger stroke by which any key is operated and having means for effecting relative lateral shifting movement between said levers and said arms to enable the arms to be operated by the levers, and tabulating devices operated by said arms.

9. In a typewriting machine, the combination with a carriage and a set of keys, a set of levers operated thereby, of a rock-shaft, a set of arms fixed upon said rock-shaft and disposed in echelon, said arms normally inoperable by said levers, a bar extending along said keys to be operated by the same finger stroke by which any key is operated, and having means for effecting relative shifting movement between the rock shaft and the levers to enable the latter to operate said arms, a stop variably shiftable by said rock shaft, and means co-operating with said stop to arrest the carriage in a position corresponding to the selected key.

10. In a typewriting machine, the combination with a carriage, a set of key-operated levers, and a set of figure types operated by said levers, of a rock-shaft, a set of arms fixed upon said rock-shaft and disposed in echelon, said arms normally inoperable by said levers, means for shifting said rock shaft endwise to bring said arms into position to be operated by said levers, a stop variably shiftable by said rock shaft, means co-operating with said stop to arrest the carriage in a position corresponding to the selected key, means for limiting the movements of the levers to prevent the types from printing when said arms are being operated, said limiting means comprising a universal bar operable by any of said key-operated levers, an arm connected to said universal bar, and a stop for said arm; said stop and arm being normally ineffective but being relatively shiftable with said shifting means to render them effective.

11. In a typewriting machine, the combination with a carriage, a set of key-operated levers, and a set of figure types operated by said levers, of a rock-shaft, a set of arms fixed upon said rock-shaft and disposed in echelon, said arms normally inoperable by said levers, means for shifting said rock shaft endwise to bring said arms into position to be operated by said levers, a stop variably shiftable by said rock shaft, means co-operating with said stop to arrest the carriage in a position corresponding to the selected key, a universal bar operable by any of said key-operated levers, said universal bar connected to said rock shaft to shift therewith, an arm connected to said universal bar, and a stop normally out of the path of said arm but in the path of the arm when the arm is shifted with the universal

bar, to arrest the key-operated levers and the types, to prevent the latter from reaching the printing point.

12. In a typewriting machine, the combination with a carriage and a set of key-operated levers, of a rock shaft, a set of arms fixed upon the rock shaft and disposed in echelon, said arms normally inoperable by said levers, a key having means for shifting the rock shaft to bring the arms beneath the levers, a stop, an arm upon said rock shaft to shift said stop variably, means coöperating with said stop to arrest the carriage in a position corresponding to the selected key, a universal bar operable by any of said key levers and connected to said rock shaft to shift therewith, a carriage-releasing member, and an arm upon said universal bar normally ineffective but shiftable with the universal bar to position to engage said carriage-releasing member.

13. In a typewriting machine, the combination with a carriage and a set of key-operated levers, of a rock-shaft, a set of arms fixed upon the rock shaft and disposed in echelon, said arms normally inoperable by said levers, a key having means for shifting the rock shaft to bring the arms beneath the levers, a stop, an arm upon said rock shaft to shift said stop variably, means coöperating with said stop to arrest the carriage in a position corresponding to the selected key, a universal bar operable by any of said key levers and connected to said rock shaft to shift said stop variably, means coöperating with said stop to arrest the carriage in a position corresponding to the selected key, a universal bar loosely mounted upon said rock shaft to shift therewith, and operable by any of said levers, said universal bar being provided with an arm, and a carriage-releasing device not normally engageable by said arm, said arm shiftable with the rock-shaft into position to operate said carriage-releasing device.

14. In a typewriting machine, the combination with a set of type-operating key-operated levers, arms normally inoperable by said levers, means for shifting said arms to positions to be operable by said levers, tabulating devices operable by said arms for said carriage, a universal bar engageable by said levers, said universal bar having an arm, means being provided to shift said arm laterally, and a stop being engageable by said arm when so shifted, so as to arrest the universal bar and the lever by which the same is depressed to prevent the types from printing, a second arm connected to said universal bar, and a carriage-releasing device operable by said second arm; the latter normally incapable of operating said releasing device, but shiftable laterally with the first arm to effective position.

15. In a typewriting machine, the combination with a carriage, of a set of key-operated levers, and a tabulating mechanism

for said carriage, including a set of arms normally inoperable by said levers, means for rendering said arms operable by said levers, said arms being movable progressively increasing distances by the levers, and said tabulating mechanism including carriage-arresting means movable correspondingly increasing distances by said arms; a universal bar operable by said levers, and a carriage-releasing device normally inoperable by said universal bar but connected to be rendered operable by said universal bar at the same time that said arms are rendered operable by said levers.

16. In a typewriting machine, the combination with a carriage, a set of key-operated levers, and a set of figure types operated by said levers, of a rock-shaft, a set of arms fixed upon said rock-shaft and disposed in echelon, said arms normally inoperable by said levers, means for shifting said rock-shaft endwise to bring said arms into position to be operated by said levers, a stop variably shiftable by said rock-shaft, means coöperating with said stop to arrest the carriage in a position corresponding to the selected key, a universal bar loosely mounted upon said rock shaft to shift therewith, and operable by any of said levers, said universal bar being provided with an arm, and a carriage-releasing device not normally engageable by said arm, said arm shiftable with the rock-shaft into position to operate said carriage-releasing device.

17. In a typewriting machine, the combination with a carriage, a set of key-operated levers, and a set of figure types operated by said levers, of a rock-shaft, a set of arms fixed upon said rock-shaft and disposed in echelon, said arms normally inoperable by said levers, means for shifting said rock-shaft endwise to bring said arms into position to be operated by said levers, a stop variably shiftable by said rock-shaft, means coöperating with said stop to arrest the carriage in a position corresponding to the selected key, a universal bar loosely mounted upon said rock-shaft to shift therewith, and operable by any of said levers, said universal bar being provided with an arm, a carriage-releasing device not normally engageable by said arm, said arm shiftable with the rock-shaft into position to operate said carriage-releasing device, a stop on the framework, and an arm connected to said universal bar and normally incapable of engaging said stop, but shiftable with the rock-shaft into position to engage said stop to arrest the universal bar and prevent the types from reaching the printing point.

18. In a typewriting machine, the combination with a set of type-operating key-operated levers, arms normally inoperable by said levers, means for shifting said arms to positions to be operable by said levers, tabu-

- lating devices operable by said arms for said carriage, a universal bar engageable by said levers, and means to enable said universal bar to limit the throw of said levers during 5 the tabulating operation to prevent the types from printing; said universal bar having an arm, and means being provided to shift said arm laterally, and a stop being engageable by said arm when so shifted, so as to arrest 10 the universal bar and the lever by which the same is depressed.
19. In a typewriting machine, the combination with a carriage and a set of type-operating figure keys, of a tabulating mechanism normally inoperable by said keys, shiftable devices for rendering said tabulating mechanism operable by said keys, and a key-bar to shift said shiftable devices, said key bar extending along said set of figure 15 keys close thereto, to permit the simultaneous operation of both said bar and any figure key by a single stroke of the finger.
20. In a typewriting machine, the combination with a carriage and a set of type-operating figure keys, of a tabulating mechanism normally inoperable by said keys, shiftable devices for rendering said tabulating mechanism operable by said keys, and a key-bar to shift said shiftable devices, said 25 key bar extending along said set of figure keys close thereto, to permit the operation of both said bar and any figure key by a single stroke of the finger, said key-bar having means effective at the first part of its depression for shifting said shiftable devices, and effective during the remainder of its depression for holding said shiftable devices in shifted positions.
21. In a typewriting machine, the combination with a carriage and a set of type-operating figure keys, of a tabulating mechanism normally inoperable by said keys, shiftable devices for rendering said tabulating mechanism operable by said keys, and a key-bar to shift said shiftable devices, said key bar extending along said set of figure 30 keys close thereto, to permit the operation of both said bar and any figure key by a single stroke of the finger, a cam being operable by 35 said key-bar to shift said shiftable devices, said cam having an inclined or active portion effective during the initial portion of the stroke of the key-bar, and a dwell portion effective during the remainder of the 40 depression of said key-bar.
22. In a typewriting machine, the combination with a carriage and a row of keys, of a tabulating mechanism normally inoperable by said keys, shiftable devices for rendering 45
- said tabulating mechanism operable by said keys, a key bar extending along said row of keys close thereto, a rock shaft upon which said key bar is mounted, and means for enabling said rock shaft to shift said shiftable devices to effective positions. 50
23. In a typewriting machine, the combination with a carriage and a row of keys, of a tabulating mechanism normally inoperable by said keys, shiftable devices for rendering said tabulating mechanism operable by said 55 keys, a key bar extending along said row of keys close thereto, a rock shaft upon which said key bar is mounted, and means for enabling said rock shaft to shift said shiftable devices to effective positions, said rock shaft having a pair of arms and said key-bar having a pair of stems whereby it is pivoted on 60 said arms.
24. In a typewriting and tabulating mechanism, the combination with a carriage, of a disk having a volute set of stops, means for enabling any of said stops to cause the arrest of the carriage, a single stop to engage any of said volute set of stops, a set of keys having means to move said single stop different 65 distances to engage any selected volute stop, and a carriage-releasing mechanism operable by any of said keys, a yielding construction being provided between said single stop and a key, to enable said key to complete its 70 stroke after the arrest of said single stop, when the same key is employed repeatedly for moving the carriage from each column to the next.
25. In a typewriting and tabulating mechanism, the combination with a carriage, of a disk having a volute set of stops, means for enabling any of said stops to cause the arrest of the carriage, a single stop to engage any of said volute set of stops, a set of keys having means to move said single stop different 75 distances to engage any selected volute stop, and a carriage-releasing mechanism operable by any of said keys, a yielding construction being provided between said single stop and a key, to enable said key to complete its 80 stroke after the arrest of said single stop, when the same key is employed repeatedly for moving the carriage from each column to the next.
26. In a typewriting and tabulating mechanism, the combination with a carriage, of a disk having a volute set of stops, means for enabling any of said stops to cause the arrest of the carriage, a single stop to engage any of said volute set of stops, a set of keys having means to move said single stop different 85 distances to engage any selected volute stop, and a carriage-releasing mechanism operable by any of said keys, a yielding construction being provided between said single stop and a key, to enable said key to complete its 90 stroke after the arrest of said single stop, when the same key is employed repeatedly for moving the carriage from each column to the next. 95
27. In a typewriting and tabulating mechanism, the combination with a carriage, of a disk having a volute set of stops, means for enabling any of said stops to cause the arrest of the carriage, a single stop to engage any of said volute set of stops, a set of keys having means to move said single stop different 100 distances to engage any selected volute stop, and a carriage-releasing mechanism operable by any of said keys, a yielding construction being provided between said single stop and a key, to enable said key to complete its 105 stroke after the arrest of said single stop, when the same key is employed repeatedly for moving the carriage from each column to the next, said single stop being yieldingly connected to an actuating member, and a latch being provided to connect said key positively to said actuating members at will. 110
